(57) **CLAIM**

I claim the ornamental design for a connector, as shown and described.

DESCRIPTION

FIG. 1 is a first perspective view of an ornamental design for a connector in a first position;

FIG. 2 is a second perspective view of the connector in a first position;

FIG. 3 is a front plan view of the connector in a first position;

FIG. 4 is a rear plan view of the connector in a first position;

FIG. 5 is a right side elevational view of the connector in a first position;

FIG. 6 is a left side elevational view of the connector in a first position;

FIG. 7 is a top plan view of the connector in a first position;

FIG. 8 is a bottom plan view of the connector in a first position;

FIG. 9 is a first perspective view of the connector in a second position;

FIG. 10 is a second perspective view of the connector in a second position;

FIG. 11 is a front plan view of the connector in a second position;

FIG. 12 is a rear plan view of the connector in a second position;

FIG. 13 is a right side elevational view of the connector in a second position;

FIG. 14 is a left side elevational view of the connector in a second position;

FIG. 15 is a top plan view of the connector in a second position; and,

FIG. 16 is a bottom plan view of the connector in a second position.

The broken line showing of parts of the drawings is included for the purpose of illustrating use and environment and forms no part of the claimed design.

1 Claim, 8 Drawing Sheets
